UNITED STATES PATENT OFFICE.

HENRY G. VOIGHT, OF NEW BRITAIN, CONNECTICUT, ASSIGNOR TO SARGENT & COMPANY, OF NEW HAVEN, CONNECTICUT, A CORPORATION OF CONNECTICUT.

LOCK.

Application filed July 17, 1918. Serial No. 245,383.

To all whom it may concern:

Be it known that I, HENRY G. VOIGHT, of New Britain, county of Hartford, State of Connecticut, have invented certain new and 5 useful Improvements in Locks, of which the following is a full, clear, and exact description.

This invention relates to locks and more particularly to a pivotally mounted latch 10 bolt provided with key-operated means for swinging the latch bolt from its latched to its unlatched position.

My invention relates particularly to the type of key-operated latch which is designed 15 to be mounted upon a sliding door or lid or the cooperating frame for the same, where it is intended that the door or lid be unlocked only from the outside of the same. Such sliding doors or lids are commonly provided upon cabinets, cupboards, boxes and the like which are designed to be unlocked 20 by a key inserted from the outside.

The principal object of my invention is to provide a key-operated lock with simple but 25 efficient means for operating the above mentioned type of latch to swing its latch bolt from the locked to the unlocked position.

Another object of my invention is to provide a strong, durable spring-operated latch 30 which may be easily and inexpensively manufactured.

To these and other ends, the invention consists in the novel features and combinations of parts to be hereinafter described and 35 claimed.

In the drawing,

Fig. 1 is a fragmentary front elevation of a door or lid and the cooperating frame or casing, having my improvement applied 40 thereto, the latch being indicated in dotted lines upon the door or lid and the strike plate indicated in dotted lines upon the adjacent frame.

Fig. 2 is a sectional view taken on line 45 2—2 of Fig. 1, looking in the direction of the arrows;

Fig. 3 is a fragmentary view of the inside of the door or lid, the latch being removed in order to show the means by which the key-controlled lock is secured in place;

Fig. 4 is a plan view of the inner face of the latch, the key-barrel which operates the latch bolt and the strike plate being shown

in section, and the latch bolt being shown in its locked position;

Fig. 5 is a view similar to Fig. 4, showing the latch bolt held in its retracted position by the strike plate; and

Fig. 6 is a side view of the latch bolt removed from its latch casing.

The drawing may be briefly described as disclosing a latch 10 which is mounted upon the inner face of a sliding door or lid 11. This latch is positioned to cooperate with a strike plate 12 which is mounted upon the frame 13 for the door or lid 11. Upon the outer face of this door or lid is mounted a key-operated lock 14 which is provided with means for retracting the latch bolt in order that the door or lid 11 may be opened. As 70 above stated, the object of my invention is to improve the construction of the latch 10 and the means by which the key-controlled lock 14 is operatively connected with the latch bolt to retract the same.

The casing of the latch 10 consists preferably of a face plate 15, one edge of which is bent at a right angle thereto, as at 16, to form the forward edge of the lock casing.

This face plate is also provided with a plurality of screw holes 17 adapted to receive screws (not shown) for securing the latch casing to the member 11 upon which it is mounted. The inner face and rear edge of this latch casing preferably consist of a plate such as 18 having a marginal portion bent at a right angle thereto as at 18' to form the rear edge of the lock casing. The plate 18 may be secured to the face plate 15 by screws such as 19, the two plates being held in their spaced relation by any preferred means.

The forward edge 16 of the lock casing has a slot 20 formed therethrough, as indicated in dotted lines in Figs. 4 and 5. This slot is adapted to receive the outwardly projecting portion of the latch bolt 21 which is pivotally mounted within its casing in a manner which will be hereinafter described.

Upon the outer end of this latch bolt is formed a hook such as 22, and upon the inner end of this bolt is formed an enlarged, substantially circular portion such as 23, having a drill hole 24 formed therethrough. Surrounding this drill hole and concentric therewith is formed a rib or flange 25 which extends

outwardly from one face of the latch bolt. The latch bolt 21 is further provided with a slot 26 extending laterally therethrough and communicating with the drill hole 24, 5 as shown particularly in Fig. 6. The means for pivotally mounting the latch bolt within the latch casing consists preferably of a drill hole formed through the plate 18, to provide a bearing in which the annular rib 25 is 10 rotatably mounted, the arrangement being such that the outer periphery of the rib 25 contacts with the face of the drill hole formed in the plate 18 and rotatably supports the latch bolt within the latch casing. 15 The means which I provide for normally holding the latch bolt in its latched position consists preferably of a coiled spring 27, one end of which may be secured to a post such as 28, which is rigidly secured 20 to the lock casing, and the other end of this spring is attached to the latch bolt in any desired manner. The attaching means which I have illustrated consists of forming a notch or socket in one face of the latch bolt by cutting away the metal so that the pin 29 is produced, about which the inner end of the spring 27 is looped. The forward movement of the latch bolt, that is the extent to which the latch bolt may be swung 25 towards the pin 28 by the spring 27, is limited by one face of the latch bolt striking against an end of the slot 20 formed in the plate 15, as shown in Figs. 1 and 4. The strike plate 12 is preferably L-shaped 30 in cross-section and has the configuration shown in Fig. 2. One face of this strike plate has a slot 30 formed therein, positioned to receive the projecting end of the latch bolt 21, and this strike plate may be 35 secured to the door frame 13 by screws such as 31.

The key-controlled means which I provide for retracting the spring-operated latch bolt 21 consists preferably of a cylinder lock of a well-known construction provided with novel means for connecting the same to the latch bolt. In the particular form shown the pin tumbler lock 14 has the usual casing 32, face plate or escutcheon 40 45 33, key-barrel 34 and pin tumblers 35. The key-barrel 34 preferably has a circumferential groove formed about the same near its inner end and a blade or plate such as 36 is provided with one edge engaging this 50 55 groove in a well-known manner, in order to prevent the key-barrel from being withdrawn from its lock casing, the blade being secured to the lock casing by screws 37. Upon the outer face of the escutcheon is 60 65 preferably pivotally mounted, in a well-known manner, a cover plate 38. The means which I provide for retaining the lock casing in its proper position within the door or lid 11 consists preferably of a plate 39 and a pair of screws 40 which pass through

this plate and engage threaded lugs formed upon the lock casing 32. This plate 39 preferably has an opening 39' formed therethrough, of sufficient diameter to permit the key-barrel to be inserted through this opening, as shown in Fig. 3, the arrangement being such that the inner face of the plate 39 rests upon a shoulder formed within the door 11, and by tightening the screws 40, the lock may be firmly clamped in place 70 within the door 11. The latch casing 13 and the key-controlled lock are so positioned that the key-barrel 34 lies in axial alignment with the axis of the latch bolt 21 and the inner end of the key-barrel extends into 75 the drill hole 24 formed in this latch bolt. The means which I provide for operating the latch bolt 21 when the key-barrel is rotated consists preferably of a pin 41 which is mounted rigidly within the inner end of 80 the key-barrel and projects radially therefrom, as shown in Figs. 3, 4 and 5. This pin is so positioned that it contacts with one shoulder of the slot 26 formed through the latch bolt, the arrangement being such that 85 when the key-barrel is rotated in a right-hand direction with respect to Figs. 4 and 5, the latch bolt will be swung about its pivotal mounting so that the notched outer end 22 of this latch bolt will clear the strike 90 plate 12 and permit the latch 10 to be separated from the strike plate 12. In order that the lock 14 will not interfere with the self-locking action of the latch bolt, the notch 26 formed in the latch bolt should 95 be sufficiently wide to permit the latch bolt to be rocked about its pivotal mounting by the strike plate, as shown in Fig. 5, without this rocking movement being interfered with by the pin 41 which projects from the 100 key-barrel into this notch.

From the above description, when read in connection with the drawing, it will be apparent that when it is desired to unlock the door or lid upon which the latch 10 is 105 mounted, all that is necessary is to insert the proper key in the lock 14 and rotate the key-barrel through a short angle in a clockwise direction, so that the pin 41 which contacts with one shoulder of the slot 26 will 110 swing the latch bolt 21 about its pivotal mounting sufficiently to clear the strike plate 12, to permit the sliding door or lid 11 to be slid away from the frame or casing 13. As soon as the latch bolt has been disengaged from its strike plate the key may be 115 released, whereupon the latch bolt and the key barrel operated thereby through the pin 41 will be immediately returned to the normal protracted position by the spring 27. 120 In which position the latch bolt is ready to be snapped into engagement with its strike plate in a well-known manner without requiring the use of a key. Since the key-barrel 34 is normally in its locked po- 125 130

sition; that is, the position shown in Fig. 2 in which the key barrel is not free to rotate, it is necessary in order to permit the latch bolt to be swung by its strike plate as shown in Fig. 5, that the notch 26 be of sufficient width to prevent the inactive face or shoulder of this notch from engaging the pin 41. The inner face plate 18 of the latch casing preferably has a notch 42 cut there-

10 in, which is provided to clear the projecting pin 41 as the inner end of the key-barrel in assembling the parts, is inserted in the drill hole 24 formed in the latch bolt.

Although in describing the construction and operation of my lock, I have described the latch 10 and lock 14 as mounted upon the sliding element 11 and the strike plate 12 as mounted upon the fixed element 13, it will be obvious that the latch 10 and lock 14 20 may be mounted upon either the sliding door, or the fixed door frame; or the latch 10 may be mounted on one sliding element and the strike plate 12 on another sliding element, without in any way modifying the 25 construction or operation of my device. Furthermore, although I have illustrated a pin tumbler lock for retracting the latch bolt 21, it will be apparent that any preferred type of lock having a key-operated barrel 30 may be provided with the means herein described for operating the latch bolt 21, without departing from the scope of my invention as defined in the annexed claims:

1. Locking mechanism, comprising a 35 latch casing having a spring operated latch bolt pivotally mounted therein, a cylinder lock having a key-barrel rotatable therein, said key-barrel provided with a projection extending therefrom into operative engagement with said latch bolt to retract the same, the engagement between said projection and latch bolt constructed to permit said latch bolt to be swung about its pivotal mounting without rotating said key-barrel.

45 2. Locking mechanism, comprising a latch casing provided with a pivoted spring operated latch bolt, a cylinder lock for retracting said latch bolt, said lock having a key-barrel rotatable therein, a projection 50 upon said key-barrel, and a shoulder upon said latch bolt, said projection positioned to be moved by its key-barrel into and out of operating engagement with said shoulder.

55 3. Locking mechanism, comprising a latch casing having a spring-operated latch bolt pivotally mounted therein, a cylinder lock, a key-barrel rotatable therein, said latch bolt and key-barrel mounted in axial alignment, and means for operatively connecting said key-barrel to said latch bolt including a projection and cooperating shoulder constructed to form a lost motion connection between said key-barrel and latch bolt.

65 4. Locking mechanism, comprising a latch

casing, a spring-operated latch bolt pivotally mounted therein, a strike plate positioned to have said latch bolt automatically swung into locking engagement therewith, a cylinder lock provided with a key-barrel, said key-barrel positioned to extend into said casing, and means upon said key-barrel to retract said latch bolt upon the rotation of said key-barrel.

5. Locking mechanism, comprising a latch 75 casing, a cylinder lock, a key-barrel rotatably mounted in said lock, a latch bolt pivotally mounted within said latch case, said key-barrel and latch bolt being mounted in axial alignment, and means upon said key-barrel 80 for operatively engaging said latch bolt, said means being constructed to permit said latch bolt to be swung from its latched to its unlatched position while said key-barrel is in its locked position.

6. Locking mechanism, comprising a pivoted spring-operated latch bolt, a strike plate positioned to have said latch bolt swung into locking engagement therewith, a cylinder 90 lock having a key-barrel therein, said key-barrel positioned to lie in axial alignment with the pivot of said latch bolt, and means forming a lost motion connection between said latch bolt and key-barrel to operate the former by the rotation of said key-barrel.

7. In combination with a key-operated lock, a latch casing having a bearing comprising a hole formed in one face thereof, a spring operated latch bolt within said case, an annular rib formed upon one face of said bolt, said rib and bearing forming a pivotal mounting for said bolt, said bolt having a notch formed therein cutting said rib, and means upon said key-operated lock operatively engaging said notch.

8. In combination with a key-operated lock, a latch casing, a latch bolt provided with means for pivotally securing the same within said casing, said bolt having a clearance opening formed axially therethrough within said pivotal means, said bolt also having a shoulder positioned adjacent said opening, and means upon said key-operated lock extending into said opening and operatively engaging said shoulder.

9. In combination with a door or the like, a latch casing mounted within one face thereof, a latch bolt swingingly mounted within said casing, a cylinder lock mounted within the opposite face of said door or the like, a key-barrel therein extending through said door into close proximity to said latch bolt, and a lost motion connection between said key-barrel and latch bolt for operating the latter by means of said key-barrel.

10. In combination, a latch casing, a latch bolt swingingly mounted therein, said latch bolt having a relatively large opening formed therethrough concentric with the axis about which the bolt swings, means inde-

pendent of said opening for swingingly mounting said bolt within its casing, and a cylinder lock for operating said latch bolt, said lock having a key barrel extending into said opening and operatively connected to said latch bolt.

11. In combination, a latch casing, a latch bolt provided with pivotal means cooperating with said casing to swingingly mount the same therein, said bolt having a clearance opening formed therein, and a cylinder lock, said lock having a key-barrel extending into said opening and operatively connected to said bolt to swing the same upon its pivotal mounting.

12. In combination, a latch casing, a spring-operated latch bolt pivotally mounted therein, a strike plate positioned to have said latch bolt swung into locking engagement therewith, and a cylinder lock provided with a key-barrel operatively engaging

said latch bolt, said engagement between said key-barrel and latch bolt constructed to form a lost motion connection to permit swinging of said latch bolt by said strike plate while said key-barrel is locked against rotation.

13. In a lock, a casing, a latch pivotally mounted thereon and provided with an opening concentric with the pivot and a key operated rotatable member extending through the casing and into said opening, cooperating means upon said latch and key operated member, by means of which the former is controlled by the latter, said means being constructed to permit said latch to be swung from its latch to its unlatched position, while said key operated member is in locked position.

In witness whereof, I have hereunto set my hand on the 13th day of July, 1918.

HENRY G. VOIGHT.
